UNITED STATES PATENT OFFICE.

GEORGE W. SHIEBLER, OF BROOKLYN, NEW YORK.

DESIGN FOR A HANDLE FOR SPOONS, &c.

SPECIFICATION forming part of Design No. 19,497, dated December 17, 1889.

Application filed September 12, 1889. Serial No. 323,779. Term of patent 7 years.

To all whom it may concern:

Be it known that I, GEORGE W. SHIEBLER, of Brooklyn, in the county of Kings and State of New York, have invented and produced a new and original Design for the Handles of Spoons, Forks, &c., of which the following is a specification, reference being had to the accompanying drawings, forming part thereof, in which—

10. Figure 1 is a photographic view of the face of a spoon, and Fig. 2 is a similar view of the back of a spoon.

The leading feature of the design of the obverse side of the handle, Fig. 1, is the scroll ornaments i i' i^2 i^3 and central ornament k and the representation of a shell h at the broad end of the handle.

The leading feature of the design of the reverse side of the handle, Fig. 2, is the scroll ornaments i' i^2 and shell ornament h' and plain center l .

The leading feature of the design of the narrow shank of the handle is the representa-

tion of a twist at g with gadroon scroll and stem ornaments a b c d e f at the ends of the 25 twist.

I claim as my invention—

1. The design for the handle of a spoon or other article, consisting of the design of the raised ornaments of the obverse and of the 30 reverse sides of the handle, substantially as represented.

2. In a design for the handle of a spoon or other article, the design of the ornaments of the obverse side, substantially as represented. 35

3. In a design for the handle of a spoon or other article, the design of the ornaments of the reverse side, substantially as represented.

Signed by me this 9th day of September, A. D. 1889.

GEO. W. SHIEBLER.
